UNITED STATES PATENT OFFICE.

WILLIAM L. WALKER, OF NEW YORK, N. Y., ASSIGNOR TO WALKER SIGNAL & EQUIPMENT CORPORATION, OF NEW YORK, N. Y., A CORPORATION OF DELAWARE.

APPARATUS FOR FINDING DIRECTION.

Application filed April 12, 1922. Serial No. 552,024.

To all whom it may concern:

Be it known that I, WILLIAM L. WALKER, a citizen of the United States, residing in the borough of Manhattan, city, county, and State of New York, have invented certain new and useful Improvements in Apparatus for Finding Direction, of which the following is a full, clear, concise, and exact description.

The object of my invention is to produce an instrument or device and a method of operating the same whereby the vibratory energy received through the medium of microphones or similar receiving devices may be accurately compared as to intensity so that the direction and also the distance from which the waves emanate may be accurately determined and is in the nature of a compensator or balance.

My invention is particularly applicable to the determination of the direction of the source of the waves produced by submarine bells, tubes, cables and similar sources of vibratory energy whereby the navigation of vessels is facilitated along the coast or at other places in the ocean, or when entering harbors or other more or less confined bodies of water. With apparatus heretofore used for that purpose, difficulty has been experienced in determining the direction of a signal, particularly a sound signal, even though of comparatively high intensity, owing to the inefficient action of the receiving devices and the lack of means for accurately comparing the intensity of waves received at two or more separated points. The principal object, therefore, of my invention is to overcome the defects of apparatus heretofore used and to enable the navigator of a vessel to easily and accurately pilot the vessel on a definite course without the unnecessary alteration of the course.

In apparatus heretofore used it has been necessary in attempting to navigate a vessel in a direction having a certain relation to a sound produced by a submarine bell or similar device, to swing the ship so that the intensity of the sound received on one side of the vessel may be compared with the intensity of the sound received on the other side by successive observations. This means

that the accuracy of the course is determined by the sensitiveness of the listener's ear alone and has not been entirely satisfactory.

Briefly my invention comprises an apparatus whereby the pulsating or alternating currents produced by microphones and similar devices located on opposite sides of a vessel may be compared for intensity to give an aural and visual indication of the source of sound, its direction and distance through the medium of a single instrument or apparatus which may or may not be combined with a steering compass and which may be located in the pilot house, thereby enabling the pilot or navigator to receive the sound signals sent out by the submarine bell or similar device, and thereby ascertain its direction and steer an accurate course. To accomplish this result it may be stated in a general way that the respective microphones or similar receiving devices on the opposite sides of the vessel are connected preferably with a pair of coils provided with cores of magnetic material within which alternating or pulsating magnetic fields are produced in accordance with the currents generated by the sound wave acting upon the microphones. In the present form of the apparatus I prefer to make use of the fact that the human ear can detect and compare sounds just within the limit of audibility much more easily and accurately than when the sounds are loudly audible. The respective fields of said field coils are therefore caused to pass respectively through one or preferably a pair of coils which are in turn connected with the indicating or receiving devices, such as the usual head telephone used by telephone operators or radio operators. The alternating or pulsating currents in one or both of the second pair of receiving coils may therefore be compared and such comparison will indicate the relative intensities in the magnetic field coils connected with the microphones, and so placed as to determine the direction from which the sound is received.

By providing the receiving or secondary coil or coils with a pointer or pointers, the direction from which the sound comes may be indicated on a scale or

compass card. For a detailed description of various forms of my invention reference may be had to the following specification and to the accompanying drawings forming a part thereof in which:

Fig. 1 is a plan view of a simple form of my invention illustrating the essential parts thereof.

Fig. 2 is a sectional view taken substantially upon the line A—A, Fig. 1.

Fig. 3 is a vertical sectional view of the preferred form of my invention as at present devised.

Fig. 4 is a plan view thereof.

Figs. 5, 6, 7 and 8 illustrate schematically various connections between the telephone receivers and the receiving coils on the compensating indicator.

Fig. 9 is a schematic diagram showing the switch members and contacts developed in one plane and by which the various connections illustrated in Figs. 5 to 8 inclusive may be accomplished by one switch.

Fig. 10 is an end view of the casing of such a switch, and Fig. 11 is an interior view of the switch, showing the end of the casing removed.

Fig. 12 is a side elevation of my improved compensating indicator applied to a gyroscopic repeater compass and Fig. 13 is a plan view of the top of such a repeater compass showing parts broken away and indicating the interior mechanism schematically, and Figs. 14, 15, 16 and 17 are diagrams illustrating the method of piloting a ship by the use of my invention.

Referring to Fig. 1, the numerals 1 and 2 indicate the respective microphones or similar receiving devices located at the opposite sides of the vessel or at similar places where it is desired to observe or ascertain the direction of sound or other waves issuing from a distant point. Said microphones are connected with the usual energizing batteries 3 and 4, and also with the coils 5 and 6 mounted on the annular magnetic core 7. The core 7 is preferably made of steel or iron, laminated to reduce eddy currents and is provided with the central pole or core portion indicated at 8 which cooperates with the outer annular portion 7 to produce magnetic lines of force between said parts, as indicated by the dotted lines of said Fig. 1. The outer annular portion 7 is connected with the inner central pole or core 8 through a radial portion 9, which causes the fields of force between the pole pieces to form complete magnetic circuits in the latter. As shown in Fig. 1 the inner pole piece 8 being substantially concentric with the outer annular portion 7, the field of force produced between the said parts is substantially uniform owing to the comparatively small reluctance of the metallic portion of the magnetic circuit,

The coils 5 and 6 are preferably wound in opposite directions so that the outer ends of the annular portions of the core 7 will have the same polarity and the inner central portion 8 will have the opposite polarity, when the currents in said coils are flowing in the opposite directions through them. This will produce lines of force within the connecting piece 9 as indicated by the arrows. Mounted so as to be movable upon the annular core 7 are two coils 10 and 11 connected respectively with the telephone receivers 12 and 13. The coils 10 and 11 are also preferably wound in opposite directions with reference to each other and are preferably mounted on supporting arms 14 and 15, one of which is illustrated in section in Fig. 2, and are each provided with pointers 16 and 17 respectively which determine their relative positions by reference to a scale 18 carried on the central pole piece or core 8.

Referring now to Fig. 1, it will be appreciated that, assuming the vessel is pointed directly toward the source of sound, the microphones 1 and 2 will produce substantially equal pulsating currents in the coils 5 and 6. These currents will cause pulsating magnetic fields of substantially equal intensity to be produced in the two halves of the annular core which in turn will induce substantially equal alternating currents in the receiving coils 10 and 11 and sounds of equal intensity in the telephone receivers 12, 13. The coils 10 and 11 being near the upper ends of the annular core 7 will be near if not at the limit of audibility of the sounds produced by the magnetization of the core, and if the sounds produced in the telephone are not audible, each of the coils is moved slightly toward the primary coils until such sounds become just audible in each telephone. Under the conditions first above pointed out, assuming that the sounds are just audible in the positions of the coils indicated in Fig. 1, it is obvious that the apparatus will indicate that the vessel is pointed directly toward the source of sound or that the latter is "dead ahead". Should the sound received by one microphone, such as the microphone 1, be greater than that received by the microphone 2, the pulsating field produced in the left hand side of the annular core 7 will be greater than that produced in the right hand side. Therefore, in order to make the sounds in the telephone 13 just audible to the listener, the coil 11 will have to be moved toward the coil 6 until such audibility is noted in the telephone 13. Supposing the coil 11 to be placed at another point, such as that indicated by the letter B, Fig. 1, it is then apparent that the pointer 17 will indicate on the scale a point opposite the numeral 180, and the direction of the sound signal will, therefore, be at a point approximately

midway between the latter numeral and 135, or about 157 degrees, thus indicating that the source of sound is approximately 22 or 23 degrees off the starboard bow of the vessel.

- 5 When this is determined, the navigator may then shift the course approximately 22 or 23 degrees to starboard from the former course, and if the source of sound is then brought dead ahead, the coil 11 may be
 10 moved to the position indicated in Fig. 1, and at which positions the sounds in the respective telephones will be just audible. If, however, coil 11 does not have to be moved to a position symmetrical with that of coil
 15 10, then the angle between the course and the direction of the sound thereby found, and the vessel is then turned a few degrees to compensate therefor and another comparison made. This method of procedure indicates in general the manner of using my device and applies also to modification herein-after described. It is obvious that only one coil may be used to determine both points of minimum audibility by shifting the same
 25 successively from one such point to the other but in such a case the pointer would be in alignment with the supporting arm of the coil rather than at an angle thereto as shown.

The different ways of connecting the telephones 12 and 13 with the coils 10 and 11 are indicated in Figs. 5 to 8 inclusive, Fig. 8 corresponding to the connections shown in Fig. 1. However, it may be desirable to connect the receiving coils 10 and 11 in series 30 with each other and in series with each telephone as indicated in Fig. 5, in which case the coils 10 and 11 are preferably superposed one above the other or may be fixed 180 degrees apart, and the connection provided 35 with a single pointer. This, however, requires comparison of the sounds in the receiver at two different points on each of the annular arms of the core as will be herein-after described in connection with a modification illustrated diagrammatically in Fig. 40 9. It also may be desirable to compare audibility of the sounds produced in the respective microphones by comparing the intensity of the currents in the coils 10 and 11 separately, in which case the telephones may be 45 shifted from one coil to the other, and the sounds compared successively instead of simultaneously.

Figs. 9, 10 and 11 illustrate one form of switch for accomplishing the connections last above referred to by the simple turning of a knob.

Referring now to Fig. 9, the preferred form of the apparatus is illustrated schematically at the upper right hand portion of this figure. The cores in this form of apparatus consist of two pairs of concentric laminated rods or bars of steel or iron superposed one above the other, as will be appreciated from a consideration of Fig. 3. One

pair of concentric bars, as indicated by the numerals 19 and 19' extend from the connecting piece 20 to their opposite ends 21 and 21', while the other or lower pair of bars 22 and 22' extend from the connecting piece 23 to their opposite ends 24 and 24'. The coil R which corresponds to the coil 6 of Fig. 1 is fixed on the lower outer annular bar adjacent the connecting portion 23, while the coil R' which corresponds to the coil 5 in Fig. 1 is located on the upper outer annular member 19 adjacent the connecting piece 20. The movable coils C and C' correspond respectively to the movable coils 11 and 10 of Fig. 1, the former being movable on the lower annular bar 22, while the coil C' is movably located on the upper annular bar 19.

It will be noted, both in Fig. 1 and in Fig. 9 that the inner and outer portions of the cores are concentric with each other, but I do not wish to be limited to this arrangement, as they may be arranged so that different portions will be at varying distances from their respective branches between which the lines of force pass, thus varying the intensity of the fields of force at different points, should it be necessary to change the spacing of the divisions on the scales or for other reasons.

Referring now to Figs. 3 and 4 in which the mechanical details of the device, as shown schematically in Fig. 9, are illustrated, the numerals 19 to 23 inclusive illustrate corresponding parts as in Fig. 9, and the coils C C' R and R' correspond to those in Fig. 9. In Fig. 3 it will be seen that the supporting parts consists of a base ring 25 having projections 26 through which screws may be passed in order to secure the base ring to a suitable standard or to support the device as hereinafter to be referred to. The base ring 25 carries at one point, as indicated on the left hand side of Fig. 3, a raised portion 27 upon which the connecting piece 23 for the bars 22 and 22' rest and to which it is secured by means of the screws 28 which engage a separator 29, upon the top of which the connecting piece 20 for the bars 19 and 19' rest. The connecting piece 20 is secured in position by a cross-bar 30 and screws 31 which also engage the separator 29. Similar separators, cross-bars and screws as indicated by the numerals 32, 33, 34 and 35 support and secure the bars 19 and 19', 23 and 23' at the other side of the coils R and R', as indicated in Fig. 4. The raised portions 27 connected with the base ring 25 carry at their inner ends supporting arms 36 which hold in position a bearing member 37. The separator 29 carries at its inner side an arm 38 which supports an upper bearing member 39. The shaft 40, having nuts 41 and 42 on the opposite ends thereof, passes

through the bearing members 37 and 39. A pressure spring 43 is interposed between the nuts 42 and the bearing 37 in order to produce a slight pressure and friction on the bearings 37 and 39 and the parts included between the same. On the shaft 40 is a flange or washer 40' which is preferably fixed thereto so as not to turn and this separates the hubs 44 and 45 carrying arms 10 46 and 47 which support the coils C and C' respectively. This support is provided by suitable transverse plates 48 and 48' attached to the arm 46 and plates 49 and 49' attached to the arm 47 and between which 15 the respective coils are wound on suitable tubes. At the outer ends of the arms 46 and 47 are transverse pieces 50 and 51 respectively to which are attached two pointers 52 and 53. The upper bar 51 carries 20 a screw threaded pin 54 having a knurled knob 55. The lower end of the pin 54 is adapted to enter a recess in bar 50 so that the two arms 46 and 47 and consequently the coils C and C' may be made to move 25 in unison, being thereby rigidly connected.

The base ring 25 also carries a series of brackets 56 which support an external ring 57, being divided into degrees or otherwise marked to enable the user to determine the 30 relative angular position between the coils R and R' and the coils C C', either when the latter are moved in unison or separately. The terminals of the coil R' are connected with the binding posts 58 and 58' while the 35 coil R is connected with the binding posts 59 and 59'. The coil C is connected with binding posts 60 and 60' on the tie plate 30, while the coil C' is connected with the binding posts 61 and 61' on the same plate. 40 These binding posts allow the respective coils to be connected with the respective switch contacts 61 of the switch as illustrated in Figs. 9, 10 and 11. The operation of this switch will now be described.

45 Referring to Figs. 9, 10 and 11, the numeral 61 indicates a series of strips of spring metal, eight in number, adapted to engage the contact members 62 carried on a rotary cylinder or drum 63, and in this case they 50 are indicated as screw-heads in Fig. 11. These contact members are arranged on longitudinal lines or elements of the cylinder 63, as indicated by the numerals (5), (6), (7) and (8) which correspond to the 55 circuit arrangements indicated in Figs. 5 to 8 inclusive. The numeral 64 indicates the transverse connection between the left hand circumferential series of contact members of Fig. 9. The dotted lines in Fig. 11 indicate how the various connections shown in Fig. 9 are made through the interior of the cylinder 63.

Without tracing the various circuits, it 60 may be stated that, when the spring contact members 61 are in contact with the rotary

contact members 62 along the horizontal line (5) the coils C C' and the telephones P P' will be connected as indicated in Fig. 5. When said spring contact members 61 are in contact with the rotary contact members 62 along the line (6), Fig. 9, the coils C C' and the telephones P' will be arranged as indicated in Fig. 6. In like manner the contacts along the line 7 will arrange the coils and telephones as indicated in Fig. 7 70 and when contacts are made along the line (8) the coils and telephones will be arranged as in Fig. 8.

75 Referring now particularly to Figs. 3, 4 and 5, it will be noted that the coils C and C', in Figs. 3 and 4, are superposed one above the other and rigidly connected by the screw pin 54. Obviously this necessitates the operation of the apparatus by a movement of the two coils at the same time. The 80 coils C and C' are preferably connected so as to oppose each other; that is, when a current is generated in the coil C a current of opposite potential is generated in the coil C'. The operation of the apparatus as thus arranged is as follows:

85 The observer first places the two rigidly connected arms and coils in such a position that the sound in the telephones is just audible on one side of the center line of the instrument running forward and aft of the ship. Assume that such a position is at the point S or 90 degrees on the starboard side as in Fig. 4, the combined coils are then moved to the other side of the instrument to a point 90 where the sound is just audible at the port side, as indicated in dotted lines at the position P in Fig. 4. It will thus be seen that the two successive positions of the combined 100 coils are separated by approximately 127 degrees. The mid position between the points is therefore one half of this position plus 90 or approximately 153 degrees on the starboard side of the scale, as indicated by the 105 arrow in Fig. 4. The course of the ship, 110 therefore, relative to the source of sound is in the direction of the arrow. In other words, the source of sound is about 27 degrees off the port bow. If it is desired to maintain the course thus ascertained relative to the source of sound, it is only necessary to check these readings from time to time as the vessel proceeds, allowing, of course, for the change of angle due to progress of the vessel.

115 If it be desired to locate the direction of the sound more accurately, the course of the vessel is changed, so that it will be about 26 degrees to the starboard of the first course. Successive readings are then taken from the 120 scale, as above indicated, and if the angles between the coils and the center line of the ship are equal, it will be known that the source of sound is dead ahead. On the other hand, if a slight difference between the an-

gles of the coils with the center line of the ship still exists, the course is again changed until said angles are the same.

The last described method of determining direction by using the coils superposed and in opposition is more particularly applicable to instances where the source of sound is near at hand, say within four or five miles, as the opposed connections of the coils tend to reduce the effective action of the magnetic field in the concentric bars. In order to make the instrument more sensitive when the source of sound is at greater distances, say ten miles or more from the vessel or receiving station, the positions of the coils for the beginning of audibility may be determined by use of the switch of Figs. 9-11, so that the operation between the coils and the telephones will be as in Figs. 6 and 7; that is, the coil C is first connected with both telephones in series, and the audibility point determined. This is indicated by the position of the switch illustrated in Fig. 10. The switch is then turned so that the pointer 66 is at the position indicated by P, P', C', in Fig. 10, at which point the coil C' will be in series with the telephones. The point of minimum audibility is then determined for the coil C'. The angle between the two positions of the respective coils thus found is then used to indicate the course, and the subsequent piloting of the vessel, as before described. The reason that the apparatus is more sensitive by using this latter procedure is that the resistance of one coil only is interposed between the telephones and their opposed currents eliminated. Substantially the same procedure is followed with the telephones connected as in Fig. 8, in which position each coil is more sensitive to the magnetic field of force than in either of the prior cases, and in this connection it is obvious that the sound produced in the telephones by the coils C and C' may be compared simultaneously by a skillful operator. If the operator cannot compare the sound simultaneously, it is only necessary to alternately connect and disconnect each telephone with its respective coil until the positions of the respective coils are determined with regard to the minimum audibility in each coil, in which case the course is determined as before. By this arrangement the resistance of the circuits in which each coil is placed is reduced by one half the resistance of the telephone circuit, since the telephones are independently connected with the coils and the sensitiveness of the apparatus is therefore still further increased.

If it be desired that the navigator may observe the course of the ship accurately by compass, and at the same time observe the direction of the sound relative to the course of the ship and also relative to the true north, the compensating indicator may be

mounted upon the top or frame of a compass, preferably a gyroscopic repeater compass of the type indicated in Fig. 13, which is controlled electrically in the manner well known in the art, from a master gyroscopic compass located in another part of the vessel, such electrical control being schematically within the broken-away portions of Fig. 13. Such a gyroscopic compass is supported upon a gimbal ring 70 having the 75 gimbal bearings 71 and 71' indicated in Fig. 12, the electrical operating mechanism for the repeater compass being contained in the casing 72 and the whole being mounted upon a vertical column or standard 73. 80 Screws 74 passing through the projections 26 referred to in connection with Fig. 3 retain the base ring 25 in position upon the repeater compass.

Referring now to Figs. 14 to 17 inclusive, 85 these figures illustrate the various steps in ascertaining the direction of the source of sound by the manipulation of the compensating indicator as previously described. In each of these instances, the coils C and C' 90 are indicated as being independently movable with the telephones connected as shown in Fig. 8. Fig. 14 illustrates the relative positions of the course, the bell and the ship when the first observations are taken in 95 either one of the ways previously described. Fig. 15 illustrates the second observation where the course has been changed to more nearly approximate that of the source of sound, while Fig. 16 indicates the second 100 change in course through the small remaining angle, so that the source of sound is dead ahead.

Fig. 17, compared with Fig. 16, illustrates, roughly, how the distance between 105 the source of sound and the vessel may be determined. Obviously, when the vessel is nearer the source of sound, the effect of the sound waves upon the microphone coils R and R' will be greater, thus establishing 110 stronger variations of the magnetic fields in the annular cores. This, in turn, produces stronger induced currents in the coils C and C', and consequently louder sounds in the telephones. The points of minimum 115 audibility will therefore be indicated by positions of the movable coils which are further removed from the fixed coils than when the distance of the source of sound is farther away. Obviously, intermediate positions will be indicated as the distance from the source of sound varies. Thus, after the initial use of the apparatus at varying known distances from sources of sound, the scale may be calibrated or may be used to 120 indicate approximately the distance of the vessel from the source of sound in subsequent navigational observations. Such calibration or readings should of course be so made as to take into account the various con- 125 130

nections of the telephones which affect the sensitiveness as indicated by the different connections in Figs. 5 to 8 inclusive.

It is obvious that instead of the receiving devices in the form of microphones, other receiving devices, such as loops or coils may be used for detecting radiant electric or magnetic energy with or without amplifying devices, as is already known in the art.

10 Having thus described the principles of operation and construction of my invention, I do not wish to be understood as being limited to the details of form and arrangement of parts herein set forth, for various changes may be made by those skilled in the art without departing from the spirit and scope of my invention as set forth in the following claims.

What I claim and desire to protect by Letters Patent is:

1. Apparatus for determining the direction and distance of sources of vibratory energy comprising, electrical receiving devices located at spaced points and adapted to produce variable electric currents in accordance with the intensity of the received waves, coils connected therewith for producing magnetic fields whose intensities vary in proportion to said currents, spaced cores of magnetic material therein adapted to form air gaps having fields of progressive intensity, a movable coil located in said fields and adapted to be placed at various points therein where the intensities thereof are equal and means for comparing the strengths of the currents in said movable coil at said points in said field.

2. Apparatus for determining the direction and distance of sources of vibratory energy comprising, electrical receiving devices located at spaced points and adapted to cause variation in electric currents in accordance with the intensity of the received waves, coils connected therewith for producing magnetic fields whose intensities vary in proportion to said currents, spaced cores of magnetic material therein adapted to form air gaps having fields of progressive intensity, coils movable within said fields and adapted to be placed at points therein where the intensities thereof are equal, and means for determining the strengths of the currents in said coils and for comparing the latter at various points in said field.

3. Apparatus for determining the direction and distance of vibratory energy comprising, electrical receiving devices located at spaced points and adapted to vary electric currents in accordance with the intensity of the received waves, coils connected therewith for producing magnetic fields whose intensities vary in proportion to said currents, spaced cores of magnetic material therein adapted to form air gaps having

fields of progressive intensity, coils movable within said fields and adapted to be placed respectively at separated points therein where the intensities are substantially the same, and means for audibly comparing the respective strengths of the currents in said movable coils.

4. Apparatus according to claim 2 in which said movable coils are adjustable along said cores. 75

5. Apparatus according to claim 3 in which said movable coils are adjustable along said cores.

6. Apparatus according to claim 1, in which the air gaps are of equal length between the cores so as to produce fields of force in said cores of substantially uniformly varying intensity. 80

7. Apparatus according to claim 2, in which the air gaps are of equal length between the cores so as to produce fields of force in said cores of substantially uniformly varying intensity. 85

8. Apparatus according to claim 3, in which the air gaps are of equal length between the cores so as to produce fields of force in said cores of substantially uniformly varying intensity. 90

9. Apparatus according to claim 1, in which the magnetic fields are generated in said cores of magnetic material having poles equally spaced apart transversely, said movable coils being adjustable along said poles. 95

10. Apparatus according to claim 2 in which the magnetic fields are generated in said cores of magnetic material having poles equally spaced apart transversely, said movable coils being adjustable along said poles. 100

11. Apparatus according to claim 3 in which the magnetic fields are generated in said cores of magnetic material having poles equally spaced apart transversely, said movable coils being adjustable along said poles. 105

12. Apparatus according to claim 1, in which the magnetic fields are generated in said cores of magnetic material having concentric poles, said movable coils being adjustable along said poles. 110

13. Apparatus according to claim 2, in which the magnetic fields are generated in said cores of magnetic material having concentric poles, said movable coils being adjustable along said poles. 115

14. Apparatus according to claim 3 in which the magnetic fields are generated in said cores of magnetic material having concentric poles, said movable coils being adjustable along said poles. 120

15. Apparatus according to claim 1, in which the respective magnetic fields are generated in said cores of magnetic material having poles annular in shape and superposed in parallel planes, said movable coils being adjustable along said poles. 125

16. Apparatus according to claim 2 in 130

which the respective magnetic fields are generated in said cores of magnetic material having poles annular in shape and superposed in parallel planes, said movable coils being adjustable along said poles.

17. Apparatus according to claim 3 in which the respective magnetic fields are generated in said cores of magnetic material having poles annular in shape and superposed in parallel planes, said movable coils being adjustable along said poles.

18. Apparatus according to claim 2 in which the means for comparing the strength of currents are provided with a switch whereby said movable coils may be connected in series with each other and with said means, or each alone in series with said means or each in parallel respectively with portions of said means.

19. Apparatus according to claim 3 in which the means for comparing the strength of currents are provided with a switch whereby said movable coils may be connected

in series with each other and with said means, or each alone in series with said means or each in parallel respectively with portions of said means.

20. Apparatus according to claim 2 in which the means for comparing the strength of currents are a pair of head telephones, and a switch whereby said movable coils and said telephones may be connected in series, or either of said coils alone may be connected in series with said telephones, or each of said telephones may be connected with one of said coils simultaneously.

21. Apparatus according to claim 3 in which the means for comparing the strength of currents are a pair of head telephones, and a switch whereby said movable coils and said telephone may be connected in series, or either of said coils alone may be connected in series with said telephones, or each of said telephones may be connected with one of said coils simultaneously.

WILLIAM L. WALKER.
